UNITED STATES PATENT OFFICE.

WENDELL P. HAMMERS, OF DUBLIN, TEXAS, ASSIGNOR OF ONE-THIRD TO HENRY DOSSETT, OF EASTLAND COUNTY, TEXAS.

WINDOW-SHADE SUPPORT.

1,120,935.

Specification of Letters Patent. Patented Dec. 15, 1914.

Application filed July 7, 1913. Serial No. 777,759.

To all whom it may concern:

Be it known that I, WENDELL P. HAMMERS, a citizen of the United States, residing at Dublin, in the county of Erath and 5 State of Texas, have invented certain new and useful Improvements in Window-Shade Supports, of which the following is a specification, reference being had to the accompanying drawings.

10 This invention relates to window shade supports, and it more particularly relates to adjustable curtain, drapery and shade supports combined.

An object of the invention is to provide a 15 device of this character which is strong, durable, simple of construction, adjustable, collapsible, neat, comparatively inexpensive, light, easy of application and thoroughly effective for the purposes intended.

20 In the accompanying drawings, which supplement this specification, Figure 1 is a front elevation view of my improved combination supporting device; Fig. 2 is an enlarged vertical sectional view transversely 25 of the device; Fig. 3 is a perspective view of the adjustable supporting bracket; and Fig. 4 is a longitudinal sectional view through one of the tubular telescoping poles.

30 Referring to these drawings, in which similar reference characters correspond with similar parts throughout the several views, the supporting bracket 10 comprises two adjustably connected sections 11 and 12 35 respectively. The major portion of the section 11 is rectilinear, being formed from sheet metal, and having its opposite edges formed with in-turned flanges 13. The major portion of the member 12 is also rectilinear, being formed from sheet metal, and is adapted to be snugly fitted between the flanges 13 and adapted for longitudinal 40 movement and adjustment therein.

The outer end of the member 11 is bent 45 substantially at right angles to the rectilinear portion thereof and is formed with apertures for engagement with the curtain pole, drapery pole and shade roller, to be hereinafter described. The outer end of the 50 member 12 is bent outward substantially at right angles to the major portion, and this outwardly extending supporting arm 15 is provided with apertures which correspond with those of the arm 14 except that the 55 aperture or slot 16 is elongated for the pur-

pose of receiving the non-rotatable axle of the shade roller. Apertures 17 may be provided in the members 11 and 12 for the reception of screws or other suitable anchoring means; or the bracket may be supported 60 on the window frame by any other suitable and proper means.

The arms 14 and 15 are preferably curved upward, and the apertures 16, 18 and 19 are located in different vertical planes, so that 65 the shade roller and curtain poles engaged therewith support the curtain, drapery and window shade in such relation to each other that there is no conflict or interference when they are manipulated.

70 The curtain pole and drapery pole may be of similar or identical construction, or they may be slightly different either in construction or in dimensions or both; but in the present instance, a description of one of 75 these poles may be applied to the other. Each pole comprises two telescoping inner sections 20 and 21, and two outer sections or ends 22. The sections 20 and 21 are preferably formed of relatively thin and light 80 tubing, or any proper material, and are adapted to telescope with one another, so that the pole may be lengthened or shortened, so as to fit window frames of different widths. The end of each section 20 and 21 85 is provided with an outwardly flared or bell-shaped socket member 23 which is screw-threaded internally for the reception of a screw 24 which is fixedly united with a bell-shaped element 25, the latter forming 90 an element of the end member 22. The apertures 19 are adapted to receive the screws 24 of the curtain pole, while the apertures 18 receive the screws 24 of the drapery pole, and the apertures 16 and 16' 95 receive the non-rotatable and the rotatable axle members, respectively, of the shade roller.

As previously mentioned, it will be seen that the window shade is supported adjacent 100 to the window frame, the tapestry is supported inwardly of the shade, and the lace curtain is supported inwardly of the tapestry, so as to impart a very artistic and ornamental effect to the window; and at the 105 same time providing for easy adjustment of the window shade, tapestry and curtain without interference of one of these members with the other.

The several members of this device being 110

collapsible, it is obvious that it may be packed in a relatively small package for shipment and storage. It is also obvious that the curtain pole and drapery pole may be easily removed independently of each other, and without interference with the window shade, by simply removing the end members 22; whereupon the curtain or drapery may either be cleaned or renewed 10 and replaced with ease and facility.

It will be seen that I have provided a device of this character which is fully capable of attaining the foregoing objects in a thoroughly practical and effective manner.

15 I do not limit my invention to the exact details of construction, combination, and arrangement of parts, as herewith illustrated and described, but my invention may only be limited by a reasonable interpretation of 20 the claim.

I claim—

In a window fixture, a supporting bracket

comprising two flat sections slidably engaged with each other, each of said sections having at its outer end an arm outstanding 25 at right angles, said arm terminating in an upwardly directed extension, means provided in said arms to support a curtain roller, a telescoping rod secured in said extensions adjacent the junctions of said extensions with the arms, and a second telescoping rod secured in the extensions adjacent their upper extremities in advance of the first named rod whereby the roller is supported rearwardly of and in a plane 30 below the first named rod and the second named rod is supported in a plane above and forwardly of the first named rod.

In testimony whereof I hereunto affix my signature in the presence of two witnesses. 40

WENDELL P. HAMMERS.
